UNITED STATES PATENT OFFICE.

BARNETT ROSENBERG, OF CHICAGO, ILLINOIS.

DESIGN FOR A HAT-RACK.

No. 37,650.

Specification for Design.

Patented Nov. 7, 1905.

Application filed September 15, 1905. Serial No. 278,678. Term of patent 7 years.

To all whom it may concern:

Be it known that I, BARNETT ROSENBERG, a citizen of the United States, residing at Chicago, in the county of Cook and State of Illinois, have invented a new, original, and ornamental Design for a Hat-Rack, reference being had to the accompanying drawing, forming a part thereof.

The drawing is a front elevation of the hat-rack.

I claim—

The ornamental design for a hat-rack as shown.

BARNETT ROSENBERG.
